4 Claims. (Cl. 139—247)

The invention relates to an automatic loom and more particularly to a mechanism for such looms with a pivoted sley and a plurality of pirns adapted to be inserted selectively into a shuttle.

It is a first object of the invention to provide means contributing to wind the pirns on the machine itself.

A further object of the invention is the provision of means so that the weft yarns come undoubtedly into a position beneath the tongue of the shuttle after pirn change.

It is another object of the present invention to provide means facilitating an efficacious structure for changing the pirns on an automatic loom, which structure is relatively simple, has a few moving parts and is extremely accurate in its operation, without necessitating the use of expensive and complicated control means.

These and other features, capabilities and advantages of the invention will appear from the following detailed description of one embodiment, illustrated in the accompanying drawings.

FIG. 1 shows a side view of the device with several pirns,

FIG. 2 is a plan view of the device shown in FIG. 1,

FIG. 3 is a diagrammatic view of the device during the pirn change,

FIG. 4 shows diagrammatically a further view of the device in another position of the sley,

FIG. 5 is a view of the various positions of the crank shaft for driving the sley,

FIG. 6 is a front view of a part of a shuttle with an inserted pirn, and

FIG. 7 is a cross-section through the shuttle on the line VII—VII of FIG. 6.

The device is intended for a loom with automatic pirn or bobbin change in which the wound pirns 2 are supplied one over the other in a shuttle box 1. The empty pirns are wound with yarn on the machine itself. This winding mechanism is no part of the invention and therefore it is not in further details explained. The lowermost pirn 2 in this mechanism which is not inside of a shuttle is forced into a shuttle when changing of the pirns, as will be described later with reference to FIG. 2. The yarn ends of the pirns 2 are held by a constantly rotating holding drum 8 covered with felt or the like. The rotary axis of this drum extends vertically and the drum is held by a bearing 38. The position of this drum 8 is determined by shuttle box 1 and other mechanisms and cannot be varied to a substantial extent.

The lowermost pirn 3 of the full wound pirns 2 stored in the shuttle box 1 lies directly over the shuttle 4 when the sley 243 of the loom lies in its foremost position shown in FIG. 3. The foremost position of the sley corresponds to the position I of the crank (see FIG. 5).

For pirn change a striker 6 acts directly over the lowermost pirn 3 disposed above the shuttle and forces it into the inside of the shuttle 4 (FIG. 3) whereby simultaneously the empty pirn 7 falls downwardly. The yarn ends or yarn tails 9 projecting from the pirns 2 are held constantly taut but not pulled out by the rotating felt drum 8.

At the moment of pirn change the shuttle 4 is in the position I' (FIG. 2) and the yarn 9a drawn from the pirn 3 thus runs in the axial direction of the pirn towards the

2

drum 8. The pick for effecting the movement of the shuttle and thus its traverse across the loom is however effected at a somewhat later moment, that is in fact when the crank rod has already reached the position II (FIG. 5) and thus the shuttle has reached the somewhat displaced position II' (FIG. 2).

In order that the yarns 9 shall not adopt the inclined position 9b shown in chain lines in FIGS. 2 and 6, in which threading in the slot of the shuttle 4 would be made difficult or impossible, an adjusting yarn guide member 14 is provided which ensures that the yarn end 9 is at least approximately coincident with the axis of the pirn 3 also in the position II of the crank arm 35 or II' of the shuttle 4, that is to say it runs in line with the longitudinal axis of the shuttle. By this displacement of the yarn between the shuttle 4 and the drum 8 the threading procedure can proceed regularly. The yarns can now pass in their normal position into the yarn receiving means of the shuttle, under the tongue 25 and between the brake jaws 36 (see FIG. 7) as a result of the increased pull on the yarn 9 by the striking movement of the shuttle. The increased pull on the yarn 9 has the effect that the yarn slips over the upper inclined part of the tongue 35 and is pushed under this tongue.

25 The brake jaws 36 disposed between the tongue 25 and the pirn are movable and bear yieldingly against the yarns 9c.

The adjusting yarn guide member 14 consisting preferably of bent strip material is provided with a shoulder 30 37 against which the lowermost yarn 9 of the pile of pirns bears. A rod 15 connected with an angle member 39 to the adjusting member 14 is supported in an axially displaceable manner in two bearings 16 for clamping the yarn in the moment of the striking movement of the 35 shuttle between clamping heads 15a, 15b. A lever 17 is pivoted to the rod 15 between the two bearings 16 on which a pull is exerted by a spring 18 approximately in the direction towards the crank shaft. A blocking pin 19 engaging behind a projection 20 or nose of the lever 17 40 prevents this lever initially from moving to the position shown in chain lines in FIG. 4. When pirn change is required the pin 19 is shifted upwardly by an intermediate member of the loom, not shown in the drawing, thereby the lever 17 is released and is moved under the action of 45 the spring 18 into the position shown in FIG. 4 in chain lines. Thereby it guides the rod 15 and thus the adjusting member 14 together with the yarn 9 in the direction of the arrow E (FIG. 4). Thereby the yarn 9c adopts the position shown in FIG. 2 for the position II' until the 50 shuttle 4 has reached the other side of the loom and the crank shaft 35 has rotated through the position III.

Thereafter the adjusting yarn guide member 14 is moved back again to its original position. For this purpose a return lever 21 is pivotally fastened to the rod 15 is 55 pushed into the path of an angular stop 22, rigidly fastened to the sley 23. On the return movement of the sley 23 in the direction of the arrow F as a result of the further movement of the crank shaft through position III, the return lever 21, the rod 15 and the adjusting member 14 are pressed back to the original position shown in full lines in FIG. 4 whereupon the pin 19 again drops behind the projection 20 in order to retain the lever 17 until the next pirn change is required.

Various changes and modifications may be made without departing from the spirit and scope of the present invention and it is intended that such obvious changes and modifications be embraced by the annexed claims.

What I claim is:

1. A yarn guiding device for a loom, comprising, in 70 combination, a reciprocable sley; a shuttle movable with said sley between a first position for receiving a pirn and a second position disposed to be picked, said shuttle hav-

ing yarn receiving means located in a longitudinal axis thereof; means for inserting a pирн having a yarn tail into said shuttle in said first position; retaining means for retaining the yarn tail of the inserted pирн spaced from said shuttle and being disposed in relation to said first position of said shuttle so that the yarn tail extends in the direction of said longitudinal axis in said first position of said shuttle, and at an angle to said axis in said second position of said shuttle; yarn guide means located intermediate said shuttle and said retaining means and being movable in the direction of the movement of said sley between a first position aligned with said shuttle in said first position and a second position aligned with said shuttle in said second position for slidably engaging the yarn tail and for moving the engaged and retained yarn tail to a position aligned with said longitudinal axis of said shuttle in said second position, operating means for moving said yarn guide means to said second position thereof after said shuttle with a pирн has been moved to said second position thereof so that the yarn tail is aligned with said shuttle at the start of the picking motion and adapted to be inserted into said yarn receiving means; and means connected with said yarn guide means and controlled by said sley for moving said yarn guide means back to said first position.

2. A yarn guiding device for a loom, comprising, in combination, a reciprocable sley; a shuttle movable with said sley between a first position for receiving a pирн and a second position disposed to be picked, said shuttle having yarn receiving means located in a longitudinal axis thereof; means for inserting a pирн having a yarn tail into said shuttle in said first position; holding means for holding the yarn tail of the inserted pирн spaced from said shuttle and being disposed in relation to said first position of said shuttle so that the yarn tail extends in the direction of said longitudinal axis in said first position of said shuttle, and at an angle to said axis in said second position of said shuttle; and a device including clamping means and yarn guide means located intermediate said shuttle and said holding means and being moveable in the direction of the movement of said sley for engaging the yarn tail, said clamping means clamping the yarn tail in a position aligned with the longitudinal axis of said shuttle, and said yarn guide means moving a portion of the yarn tail between said clamping means and said shuttle to a position aligned with said longitudinal axis of said shuttle in said second position whereby the yarn tail is placed in a position to be inserted into said yarn receiving means of said shuttle.

3. A yarn guiding device for a loom, comprising, in combination, a reciprocable sley; a shuttle movable with said sley between a first position for receiving a pирн and a second position disposed to be picked, said shuttle having yarn receiving means located in a longitudinal axis thereof; means for inserting a pирн having a yarn tail into said shuttle in said first position; holding means for holding the yarn tail of the inserted pирн spaced from said shuttle and being disposed in relation to said first position of said shuttle so that the yarn tail extends in the direction of said longitudinal axis in said first position of said shuttle, and at an angle to said axis in said second position of said shuttle; and a device including clamping means and yarn guide means located intermediate said shuttle and said holding means and being moveable in the

5 direction of the movement of said sley for engaging the yarn tail, said clamping means clamping the yarn tail in a position aligned with the longitudinal axis of said shuttle, and said yarn guide means moving a portion of the yarn tail between said clamping means and said shuttle to a position aligned with said longitudinal axis of said shuttle in said second position whereby the yarn tail is placed in a position to be inserted into said yarn receiving means of said shuttle; and operating means connected to said yarn guide means and including a spring connected to said yarn guide means for moving the same to engage and move the yarn tail to said aligned position, and a blocking means for holding said yarn guide means and adapted to release said yarn guide means in synchronism with the movement of said sley for movement by said spring; and means operated by said sley for moving said yarn guide means against the action of said spring until said blocking means engages said yarn guide means and blocks movement of the same.

4. A yarn guiding device for a loom, comprising, in combination, a reciprocable sley; a shuttle movable with said sley between a first position for receiving a pирн and a second position disposed to be picked, said shuttle having yarn receiving means located in a longitudinal axis thereof; means for inserting a pирн having a yarn tail into said shuttle in said first position; holding means for holding the yarn tail of the inserted pирн spaced from said shuttle and being disposed in relation to said first position of said shuttle so that the yarn tail extends in the direction of said longitudinal axis in said first position of said shuttle, and at an angle to said axis in said second position of said shuttle; and a device including clamping means and yarn guide means located intermediate said shuttle and said holding means and being moveable in the direction of the movement of said sley for engaging the yarn tail, said clamping means clamping the yarn tail in a position aligned with the longitudinal axis of said shuttle, and said yarn guide means moving a portion of the yarn tail between said clamping means and said shuttle to a position aligned with said longitudinal axis of said shuttle in said second position whereby the yarn tail is placed in a position to be inserted into said yarn receiving means of said shuttle; and operating means including a lever connected to said yarn guide means and to said clamping means, a spring connected to said lever for moving said yarn guide means to engage said yarn tail so that the same is moved to said aligned position, and for operating said clamping means to clamp the yarn tail, and blocking means for blocking movement of said lever under the action of said spring and adapted to release said lever in synchronism with the movement of said sley; and a member connected with said lever and operated by said sley during movement with said shuttle to said first position for moving said lever against the action of said spring until said blocking means engages said lever and blocks movement of said yarn guide means.
